CLAIM

The ornamental design for a scoop-like device for picking up and removing animal droppings and the like, substantially as shown and described.

DESCRIPTION

FIG. 1 is a top perspective view of a scoop-like device for picking up and removing animal droppings and the like, showing our new design;

FIG. 2 is a side elevational view of the device.

FIG. 3 is a fragmentary view showing the opposite side of the handle portion of the device;

FIG. 4 is a front view of a modified form of the scoop-like device with jaws having sides extending slightly inwardly;

FIG. 5 is a rear view of the device as illustrated in FIG. 4; and

FIG. 6 is a bottom view of the device illustrated in FIG. 4 looking towards the movable jaw portion of the device.

FIG. 3**FIG. 2****FIG. 4****FIG. 5****FIG. 6**
